UNITED STATES PATENT OFFICE.

GEORGE C. L. TISCH, OF ELIZABETH, NEW JERSEY, ASSIGNOR TO TISCH MACHINE & TOOL WORKS, OF ELIZABETH, NEW JERSEY, A CORPORATION OF NEW JERSEY.

PIN GUIDE.

1,421,861.

Specification of Letters Patent. Patented July 4, 1922.

Application filed December 1, 1921. Serial No. 519,219.

To all whom it may concern:

Be it known that I, GEORGE C. L. TISCH, a citizen of the United States, and a resident of Elizabeth, in the county of Union 5 and State of New Jersey, have invented a new and Improved Pin Guide, of which the following is a full, clear, and exact description.

This invention relates to pin guides for 10 knitting machines and has for an object to provide an improved construction for guiding thread operating pins of the type disclosed in Patent No. 457,265, issued August 4, 1891.

Another object in view is to provide a 15 guiding structure for pins which will hold the returning pins in substantially a desirable position and will then re-assemble or shift all of the pins to a given starting 20 point.

A still further object of the invention is to provide a guiding member formed as a deflecting plate arranged adjacent the pins to be guided so as to receive the pins regardless of their position and move them to 25 a given starting point.

In the accompanying drawing—

Figure 1 is a side view of a pin guide embodying the invention, the same being shown 30 in connection with a pin carrying chain.

Figure 2 is a top plan view of the structure shown in Figure 1.

Figure 3 is a sectional view through the 35 guide and certain associated parts, the same being taken on line 3—3 of Figure 1.

Referring to the accompanying drawing by numerals, 1 indicates a chain used in knitting machines, as for instance, of the type disclosed in Patent No. 457,265, said 40 chain carrying a number of pins 2 which are preferably provided with heads 3 at one end. These pins are designed to be brought opposite thread bars 4 so that suitable arms and cams (not shown) may operate the pins 2 for shifting the bars 4 to 45 secure the desired design during the knitting operation. In order that the pins 2 may be always moved back to a starting point as shown at the left in Figure 2, a 50 deflecting plate or guide 5 is provided which is formed with a section 6 parallel to the chain 1 at the left end. By this construction and arrangement, the pins may be in substantially any position and will strike 55 the guide 5 at some point along the in-

clined section 7 thereof and be gradually shifted as the chain moves until the pins engage the straight section 6. This straight section is utilized for holding the pins in proper position against accidental movement in one direction so that they will pass the thread bars 4 as the chain moves unless positively operated. Immediately after passing the straight section 6, the pins are in position for being operated to shift the 65 bars 4. The bars 4 are usually shifted different distances and, consequently, the pins are forced outwardly different distances whereby they will turn substantially in the position to which they have been moved 70 so that the deflecting section 7 will cause a proper movement of the respective pins regardless of their position and eventually move them to a starting point as shown at the left in Figure 2.

The guide 5 is provided with extensions or feet 8 and 9 through which bolts are passed so as to be secured to a slotted bar 10, which slotted bar accommodates the shaft 11 on which the sprocket wheel for 80 chain 1 is mounted. A supporting bracket 12 is bolted or otherwise secured to the bar 10 and to any part of the knitting machine to provide a proper support for the bar 10 and guide 5. A depending plate 13 is also 85 bolted or otherwise rigidly secured to the bar 10 and acts as a return guard to prevent the pins from extending too great a distance on one side of the chain 1.

What I claim is:—

1. A pin guide for knitting machines comprising a plate having an inclined flat guiding section, and a straight guiding section merging therein, said plate being of such a length as to engage substantially half 95 of the pins of said knitting machine at one time.

2. In a pin guide, the combination with a knitting machine having a chain carrying pins, of a guide for moving said pins to one 100 side of the chain consisting of a section inclined in respect to the chain, and a section arranged parallel to the chain, said parallel section being arranged adjacent one end of the chain for preventing accidental 105 shifting of said pins.

3. The combination with a knitting machine provided with a chain having pins, of a guide for shifting said pins, said guide comprising a body having a section posi- 110

tioned diagonally in respect to said chain, and a second section positioned parallel to said chain for preventing accidental shifting of said pins, and a foot at each end of 5 said body, and means for rigidly securing said feet to a support.

4. The combination with a knitting ma-

chine provided with a pin chain carrying a number of pins, of a return guiding plate for said pins, and a second guide for said 10 pins formed with a diagonally collecting section, and a section parallel with the chain.

GEORGE C. L. TISCH.
